COMBINED DOOR LOCK AND AJAR HOOK

Henry G. Voight, New Haven, Conn., assignor to
 Sargent & Company, New Haven, Conn., a corporation of Connecticut

Application January 1, 1942, Serial No. 425,331

15 Claims. (Cl. 70—93)

This invention relates to door locks, and more particularly to a combined door lock and so-called "ajar hook," or a device for permitting the door to swing to partly open position but preventing it from further opening.

In connection with outside doors and doors to rooms or apartments, mechanism has sometimes been employed to permit the occupant to open the door to a limited extent, while at the same time preventing anyone on the outside from forcing the door to a further open position so that entry could be made. These devices have sometimes taken the form of chains, for example, and other times have taken the form of swinging bars cooperating with a member on the door jamb.

Although there have been some exceptions, usually these so-called "ajar hooks" or door fasteners constitute mechanism entirely separate from and independent of the door lock itself. Even where the ajar hook has been associated with the lock or latch mechanism it has been more or less independent thereof in its operation, and the release of the door from the fastening element has not been possible from the outside. That is, when the door fastener was set or engaged, it could only be disengaged by a person upon the inside of the room, and hence anyone seeking to enter from the outside must be admitted by one upon the inside.

This results in considerable inconvenience, particularly in connection with ship cabin doors, for example, where the cabin has more than one occupant. In such case it is desirable to provide for the opening of the door from the outside by a proper key, regardless of the position of the door-fastening means, so that one occupant of the cabin may set the fastening devices, and at the same time the other occupant may admit himself by means of a key without disturbing the first occupant.

One object of the present invention is to provide a combined door lock and door fastener or ajar hook of novel form and construction.

A still further object of the invention is to provide a combined door lock and door fastener such that the fastening means may be released from the outside of the door by means of a proper key.

A still further object of the invention is to provide a combined door lock and door fastener which will be simple in construction and operation, so that the door may be opened from either side thereof in the ordinary manner.

A still further object of the invention is the provision of a combined lock and door fastener

wherein the fastening means may be disengaged by the turning of the inside knob in the usual manner to open the door, so that the occupant of the room in case of emergency would not have to resort to any unusual operations to obtain an exit from the room.

To these and other ends the invention consists in the novel features and combinations of parts to be hereinafter described and claimed.

In the drawings:

Fig. 1 is a front elevational view of a combined door lock and fastener mechanism embodying my invention, the cover of the lock case being removed to show the interior mechanism;

Fig. 2 is a similar view of a portion of the lock mechanism, the parts being shown in another position;

Fig. 3 is a view similar to Fig. 2, showing the door fastening bolt at the beginning of its retractive movement;

Fig. 4 is a face view of the door strike and fastener element;

Fig. 5 is a sectional view on line 5—5 of Fig. 2; and

Fig. 6 is a sectional view of the outer end of the door fastening bolt.

To illustrate a preferred embodiment of my invention I have shown a door lock comprising a casing 10 having mounted therein a lock cylinder 11 of usual form, having a rotatable rollback 12. The casing also contains a latch bolt comprising a bolt head 13 and stem 14 guided by lugs 15 on the case, and normally urged to protruded position by spring 16. At the rear end of the stem 14 is a crosshead 17 adapted to be engaged by the lower end of a latch-retracting lever 18, the lever having a boss 19 adapted to be engaged by the rollback 12, so that the latch may be key-operated from the outside of the door.

In the casing is also mounted aligned hubs 20, only one of which is shown, which hubs are adapted to be operated by the usual doors knobs. It will be understood, however, that in this particular case the outer hub is dogged against rotation, an arm 21 being secured to the hub, the end of which is forked to engage a lug 22 secured to the case. The inner hub 23 carries a rollback 23 adapted to engage lugs 24 carried at the rear end of a latch-retracting element or yoke 25, the upper lug 24 being designed to engage the lower portion of the crosshead 17 to withdraw the latch bolt. It will be understood that the yoke is normally urged to forward position by the spring 26. The parts so far described are more or less of

usual form in door locks made at the present time wherein the latch bolt is operated from the inside by means of a knob and from the outside by means of a key.

In the present instance the strike plate comprises an upper portion 28 and a lower portion 29, the latter being offset rearwardly or inwardly, as shown in Fig. 1, from the former. To the lower portion 29 is pivoted a slotted element 30 having an elongated slot 31 slightly enlarged at its upper end, as shown at 32. The element 30 is pivoted to the strike plate by a suitable fastening element such as the screw 33, so that it may swing from the full-line position shown in Fig. 4 to the dotted line position shown in that figure, or even to a further position wherein it stands at right angles to the original position along the strike plate. It will be noted that the screw 34 at the lower portion of the strike plate merely secures the latter to the door jamb and is not engaged with the element 30. It will also be noted that the element 30 stands directly below the portion 28 of the strike plate, or within the vertical outline of this portion, so that the face of the element 30 is substantially flush with the face of the element 28.

The portion 28 of the strike plate is provided with the usual latch opening 35 to receive the bolt 13, while the lower portion of the plate is provided with a recess 36. This recess is relatively deep, as shown in Fig. 1, and as shown in Figs. 4 and 5 opens outwardly through the inner edge of this portion of the strike plate, for a reason to be hereinafter set forth.

In the lower part of the lock case is slidably mounted an auxiliary bolt or ajar hook bolt 37, this member being guided in its reciprocatory movements by means of a slot formed therein at 38 and a pin 39 carried by the lock case. This bolt has a rounded end portion 40 adapted to be protracted from the lock case, and in this portion is a latch member 41 pivoted at 42 and having lugs 43 and 44 at its front and rear ends, respectively. It will be noted that the latch member is overweighted at the forward or left-hand side of the pivot 42, as shown in Figs. 1 and 6, for example, so that when the bolt 37 is retracted the forward end of this latch will drop downwardly so that the lug 43 will stand substantially flush with the upper surface of the portion 40. However, when the bolt is protracted the lug 44 at the tail of the latch member will engage the face plate 45 of the lock case and swing the latch element to the position shown in Fig. 6, wherein the lug 43 protrudes upwardly from the slot in the bolt in which it normally stands.

A hub 47 is rotatably mounted in the lower portion of the lock case and designated to be rotated by any suitable means such as a thumb turn, for example. To this hub is secured a rollback 48 which is pivoted to a link 49 at 50, the other end of this link being pivoted at 51 to the tail 52 of the bolt 37. It will be noted that the members 48 and 49 form an operating toggle for the bolt 37. A tension spring 53 secured to a post 54 on the case at one end, and to a post 55 on the tail 52 at the other end, normally tends to urge the bolt 37 to its retracted or inoperative position.

Also secured to the hub 47 is an arm 56 adapted to stand in engagement with an arm 57 on the yoke 25 when the bolt 37 is protracted, as shown in Figs. 2 and 3. A second arm 58 is also secured to the hub 47, which arm is adapted when

the bolt 37 is thrown or protracted, as shown in Fig. 2, to be engaged by the lower surface of a laterally extending member 59 at the lower end of a slide bar 60. This slide bar 60 is movably mounted in the lock case, and at its upper end is provided with a laterally extending portion 61 designed to be engaged by the rollback 12. It may here be stated that when it is desired to operate the latch-retracting member 18 by the key from the outside of the door, the key is turned in one direction to engage the rollback 12 with the lug 19, while if it is desired to operate the slide bar 60, the rollback is turned in the other direction. It will also be noted that while the slide bar stands in its lower position, as shown in Fig. 1, when the bolt 37 is retracted in the inoperative position within the lock case, this member will be raised to an upper position when the bolt 37 is protracted, as shown in Figs. 2 and 3.

A lug 62 projects upwardly from the bolt 37 and carries a laterally projecting pin 63. This pin is designed to be engaged in an open-ended and elongated slot 64 in the lower end of a walking beam 65, pivoted to the case at 66. This walking beam is provided at its upper end with a pin 67 standing in an elongated slot 68 provided in a lug 69 secured at the rear end of the head 13 of the latch bolt. As will be explained hereinafter, the latch bolt may be freely moved without affecting the door-fastening bolt 37 if the latter is in retracted position. The connecting of the bolts by the walking beam provides that both bolts cannot be protracted at the same time, and the protraction of the fastening bolt will move the latch bolt rearwardly to its inoperative position.

The operation of the device will now be described. With the parts in the position shown in Fig. 1, the lock will operate as an ordinary door lock in that the latch bolt 13 may be freely operated either by the knob from the inside or by the key from the outside, without having any effect upon the fastening bolt 37. It will be understood that when the latch bolt is retracted the lower end of the walking beam 65 merely moves out of engagement with the pin 63, as will be permitted by the open-ended slot 64, and the latch bolt will normally be urged to protracted position by the spring 16.

If, however, the occupant of the room wishes to place the door fastening means or "ajar hook" in operation, the hub 47 is turned in an anti-clockwise direction, as shown in Figs. 1 to 3, thus straightening the toggle links 48 and 49 and protracting the fastening bolt 37. This bolt is thrown outwardly through the front plate 45 of the lock case and through the upper enlarged portion 32 of the slot 31 of the swinging element 30, the end of the bolt entering the open-ended recess 36 in the strike plate 29. As the bolt 37 approaches its fully protracted position, the tail 44 on the latch member 41 strikes against the face of the lock case and throws the element 43 outwardly to prevent its disengagement from the slot 30. This movement, it will be understood, through the walking beam retracts the latch bolt 13, as shown in Fig. 2. The door may now be swung to partly open position, the element 30 swinging from its full-line position shown in Fig. 4 to or beyond its dotted line position shown in that figure, about the pivot element 33, and the rounded head 40 of the fastening bolt riding outwardly in the slot 31, as far as is permitted by the length of this slot and the length of the

element 30. The door will be thus restrained against further opening, and it will be impossible for anyone on the outside to spring the element 30 off the end of the bolt portion 40 on account of the lug 43 on the latch member 41.

When the fastener bolt 37 is thrown, the parts stand in the position shown in Fig. 2. The occupant of the room may retract the bolt 37 by turning in a clockwise direction the hub 47. When this is done the spring 16 will immediately protract the latch bolt 13 and the lower portion of the walking beam 65 will follow the pin 63. It may be noted that it is only necessary to turn the hub 47 to a sufficient extent to break the toggle formed by the links 48 and 49, and the retraction of the bolt 37 will be effected by the spring 53. The bolt will, of course, be held in protracted position against the action of the spring by the toggle members, as shown in Fig. 2.

However, if the occupant wishes to leave the room, and particularly in case of haste or panic, he need only rotate the door knob as he would normally do, thus rotating the rollback 23, retracting the yoke 25, and causing the part 57 of this yoke to engage the arm 56, thus rotating the hub 47 and breaking the toggle to permit the bolt 37 to be retracted by its spring. Also, if a person on the outside desires to enter and is in possession of the proper key, he may retract the bolt 37 by rotating the rollback 12 in a clockwise direction, as shown in Fig. 1, thus depressing the slide bar 60 and rotating the hub 47 by means of the engagement of the part 59 with the arm 58 rigidly secured to the hub 47. Thus, when the fastening bolt is protracted, it may be retracted either by turning the inside knob or by a key from the outside, and, of course, may also be retracted from the inside by rotating the hub 47 by means of the thumb turn attached thereto.

It will also be seen that when the fastening bolt 37 is in retracted position the latch bolt operates in the normal manner without interfering with the position of the fastening bolt, in that the walking beam simply oscillates idly without moving the bolt 37. However, when the fastening bolt 37 is protracted, the latch bolt is always withdrawn, and when the bolt 37 is retracted the latch bolt will immediately be urged to protracted position by its spring, unless the bolt 37 is retracted by the turning of the knob, in which case the retraction of the yoke will also insure the retraction of the latch bolt 13 so that an occupant of the room may retract both bolts by the one operation, i. e., the turning of the inside knob.

It will also be observed that the fastening bolt 37 may be withdrawn from the swinging element 30 in any position of the latter. That is, even while the door is ajar this bolt may be withdrawn, for example, by the key from the outside, it being understood that the portion 40 of the fastening bolt is circular in cross section and is of a diameter to slide freely in the slot 31. As soon as the tail 44 of the latch member 41 no longer contacts the face 45, this latch member will drop to its normal position, in which the top of the lug 43 is flush with the outer surface of the part 40 of the bolt, so that, while it is impossible to spring the swinging element 30 away from the bolt portion 40, the bolt may be withdrawn at any time, even when the door stands ajar, by the mechanism shown.

While I have shown and described a preferred embodiment of my invention, it will be under-

stood that it is not to be limited to all of the details shown, but is capable of modification and variation within the spirit of the invention and within the scope of the claims.

5. What I claim is:

1. A door lock comprising a case, a latch bolt reciprocably mounted therein and adapted to cooperate with a strike plate, a second bolt element reciprocably mounted in the case, a slotted element mounted on the door jamb with which said second bolt cooperates to limit movement of the door to partly open position, means for protracting said second bolt, said slotted element being pivoted to the strike plate at a point below said first bolt, and spring means to retract said second bolt.

2. A door lock comprising a case, a bolt reciprocably mounted therein and adapted to cooperate with a strike plate, a second bolt element reciprocably mounted in the case, a slotted element mounted on the door jamb with which said second bolt cooperates to limit movement of the door to partly open position, means for protracting said second bolt, and a single knob means at the inside of the door for retracting both of said bolts.

3. A door lock comprising a case, a bolt reciprocably mounted therein and adapted to cooperate with a strike plate, a second bolt element reciprocably mounted in the case, a slotted element mounted on the door jamb with which said second bolt cooperates to limit movement of the door to partly open position, means connecting said bolts to effect retraction of one thereof when the other is protracted, and means for protracting and retracting said bolts.

4. A door lock comprising a case, a bolt reciprocably mounted therein and adapted to cooperate with a strike plate, a second bolt element reciprocably mounted in the case, a slotted element mounted on the door jamb with which said second bolt cooperates to limit movement of the door to partly open position, means connecting said bolts to effect retraction of one thereof when the other is protracted, and means for protracting and retracting said bolts, said connecting means between the bolts permitting normal operation of the first bolt when the second is retracted.

5. A door lock comprising a case, a bolt reciprocably mounted therein and adapted to cooperate with a strike plate, a second bolt element reciprocably mounted in the case, a slotted element mounted on the door jamb with which said second bolt cooperates to limit movement of the door to partly open position, means for protracting said second bolt, and a walking beam connected at its ends to said bolts respectively whereby the protraction of the second bolt effects retraction of the first bolt.

6. A door lock comprising a case, a bolt reciprocably mounted therein and adapted to cooperate with a strike plate, a second bolt element reciprocably mounted in the case, a slotted element mounted on the door jamb with which said second bolt cooperates to limit movement of the door to partly open position, means for protracting said second bolt, and a walking beam connected at its ends to said bolts respectively whereby the protraction of the second bolt effects retraction of the first bolt, said walking beam having a one-way connection with one of said bolts.

7. A door lock comprising a case, a bolt reciprocably mounted therein and adapted to co-

operate with a strike plate, a second bolt element reciprocably mounted in the case, a slotted element mounted on the door jamb with which said second bolt cooperates to limit movement of the door to partly open position, means for protracting said second bolt, and key-operated means for operating both bolts, said key-operated means being rotated in one direction to effect operation of one bolt and in the opposite direction for effecting operation of the other bolt.

8. A door lock comprising a case, a bolt reciprocably mounted therein and adapted to cooperate with a strike plate, a second bolt element reciprocably mounted in the case, a slotted element mounted on the door jamb with which said second bolt cooperates to limit movement of the door to partly open position, means for protracting said second bolt, a walking beam connected at its ends to said bolts respectively whereby the protraction of the second bolt effects retraction of the first bolt, and a knob at the inside of the door to effect retraction of both said bolts upon rotation in either direction.

9. A door lock comprising a case, a bolt reciprocably mounted therein and adapted to cooperate with a strike plate, a second bolt element reciprocably mounted in the case, a slotted element mounted on the door jamb with which said second bolt cooperates to limit movement of the door to partly open position, means for protracting said second bolt, a walking beam connected at its ends to said bolts respectively whereby the protraction of the second bolt effects retraction of the first bolt, a bolt-retracting member in the case, knob means at the inside of the door to actuate said member, and said member serving to retract both of said bolts.

10. A door lock comprising a case, a bolt reciprocably mounted therein and adapted to cooperate with a strike plate, a second bolt element reciprocably mounted in the case, a slotted element mounted on the door jamb with which said second bolt cooperates to limit movement of the door to partly open position, means for protracting said second bolt, means to actuate said second bolt, said means including a toggle arranged to hold said bolt in protracted position, and spring means to retract said bolt when said toggle is broken.

11. A door lock comprising a case having a latch bolt therein adapted to cooperate with a strike plate, an auxiliary bolt, a pivotally-mounted member carried by said strike plate to cooperate with said auxiliary bolt, and means to simultaneously protract said auxiliary bolt and

retract said latch bolt, said means permitting protraction and retraction of the latch bolt when the auxiliary bolt is in retracted position without movement of the latter bolt.

12. A door lock comprising a case having a latch bolt therein adapted to cooperate with a strike plate, an auxiliary bolt, means carried by said strike plate to cooperate with said auxiliary bolt, means interconnecting said bolts whereby one thereof is retracted when the other is protracted, means to protract said auxiliary bolt and thereby effect retraction of the latch bolt, and said interconnecting means having a one-way connection with one of said bolts to permit protraction and retraction of the latch bolt while the auxiliary bolt is in retracted position.

13. In a door holder, a case adapted to be mounted on the door, having a latch bolt and an auxiliary bolt reciprocably mounted therein, means swingingly mounted on the door jamb to cooperate with said auxiliary bolt to hold the door in partly open position, said bolts being interconnected whereby the latch bolt is retracted when the auxiliary bolt is protracted, and means for protracting said auxiliary bolt.

14. A door fastening device comprising a casing adapted to be mounted upon the door, a beveled latch bolt reciprocably mounted in the casing, a strike plate mounted upon the door jamb having a slotted element pivotally carried thereby, an auxiliary bolt reciprocably mounted in the casing and adapted when projected to enter said slot to limit movement of the door to partly open position, means movably mounted on said auxiliary bolt to engage said element and normally prevent disengagement therebetween when the door is in said partly open position and the auxiliary bolt is projected, and means for retracting said auxiliary bolt into the casing in any position of the door.

15. A door fastening device comprising a casing adapted to be mounted upon the door, a beveled latch bolt reciprocably mounted in the casing, a strike plate mounted upon the door jamb having a slotted element pivotally carried thereby, an auxiliary bolt reciprocably mounted in the casing and adapted when projected to enter said slot to limit movement of the door to partly open position, means movably mounted on said auxiliary bolt to engage said element and normally prevent disengagement therebetween when the door is in said partly open position and the auxiliary bolt is projected, and key-operated means for retracting said auxiliary bolt into the casing in any position of the door.

HENRY G. VOIGHT.
